UNITED STATES PATENT OFFICE

97,825

DESIGN FOR A JAR OR THE LIKE

Frasier Smith, Wheeling, W. Va., assignor to The R. T. French Company, Rochester, N. Y., a corporation of Delaware

Application October 3, 1935, Serial No. 58,815

Term of patent 14 years

To all whom it may concern:

Be it known that I, Frasier Smith, a citizen of the United States, residing at Wheeling, in the county of Ohio and State of W. Va., have invented a new, original, and ornamental Design for a Jar or the like, of which the following is a specification, reference being had to the accompanying drawing, forming part thereof.

Fig. 1 is a front view and Fig. 2 is a side view of a jar showing my new design.

I claim:

The ornamental design for a jar or the like as shown.

FRASIER SMITH.
